CLAIM

The ornamental design for a cap, as shown and described.

DESCRIPTION

FIG. 1 is a top view of a cap showing our new design; FIG. 2 is a front view thereof; and,

FIG. 3 is a perspective view.

The dash-dash broken lines in the drawing figures are intended to show portions of the cap that are not being claimed, and thus form no part of the claimed design.

The dash-dot broken lines show a boundary between the claimed subject matter and the unclaimed portions of the recesses within the cap.
